BY-PASS DOOR GUIDE

Joseph C. Labrie, Miami, Fla.

Application April 19, 1956, Serial No. 41,133

Term of patent 14 years

(Cl. D10—7)

Fig. 1

Fig. 2

Fig. 3

I claim:

The ornamental design for a by-pass door guide, as shown.
